(57) **CLAIM**

The ornamental design for a display screen with animated graphical user interface, as shown and described.

DESCRIPTION

FIG. 1 is the first image in a sequence for a display screen with animated graphical user interface showing my new design;

FIG. 2 is the second image thereof;

FIG. 3 is the third image thereof;

FIG. 4 is the fourth image thereof;

FIG. 5 is the fifth image thereof;

FIG. 6 is the sixth image thereof;

FIG. 7 is the seventh image thereof;

FIG. 8 is the first image in a sequence for a display screen with animated graphical user interface showing an alternative embodiment of my new design;

FIG. 9 is the second image thereof;

FIG. 10 is the third image thereof;

FIG. 11 is the fourth image thereof;

FIG. 12 is the fifth image thereof;

FIG. 13 is the sixth image thereof;

FIG. 14 is the seventh image thereof;

FIG. 15 is the first image in a sequence for a display screen with animated graphical user interface showing another alternative embodiment of my new design;

FIG. 16 is the second image thereof;

FIG. 17 is the third image thereof;

FIG. 18 is the fourth image thereof;

FIG. 19 is the fifth image thereof;

FIG. 20 is the sixth image thereof; and,

FIG. 21 is the seventh image thereof.

The appearance of the animated graphical user interface sequentially transitions between the images shown in FIGS. 1-7, 8-14, and 15-21.

The outermost broken line illustrates the display screen, and the remainder of the broken lines, including the broken line showing of alphanumeric characters and envelope, illustrate portions of the animated graphical user interface. None of the broken lines form part of the claimed design.
